EDWARD MOMPESSEON MORGAN, OF WESTMOUNT, QUEBEC, CANADA.

BEATER FOR EGGS, CREAM, AND THE LIKE.

Application filed February 23, 1928. Serial No. 256,292.

This invention relates to devices for beating eggs, cream and the like, and appertains particularly to a beater characterized by dashers actuated to have an approximate elliptical oscillatory movement, the object of the invention being the simplification and improvement of the actuating mechanism and the construction of the device generally from readily formed parts and material in order to facilitate and cheapen its manufacture.

For full comprehension however of my invention reference should be had to the accompanying drawings forming a part of this specification, in which the same reference characters indicate the same parts and wherein:

Fig. 1, is a face view of my improved beater;
20 Fig. 2, is a side elevation of the beater; and
Fig. 3, is a cross-section on line 3—3

Fig. 1.
Referring to the drawings, 2 represents the frame of the beater and 3 a vertically reciprocating bar slidably mounted within the frame. Beater or dasher arms 4 are pivotally carried by the lower end of bar 3, depending therefrom and terminating in dasher portions proper 4^a of substantially flattened volutoid form, the convolutions of one dasher portion being of different measurement to the corresponding convolutions of the other to allow the dashers to pass through one another. The beaters or dashers are preferably formed of wire and the pivotal connections between their upper ends and the bar 3 are made by loosely coiling the wire, at a short distance from the end around a headed pin 5 carried by the bar, the end portions of the wires being bent at right angles to form short arms 4^b extending transversely respectively in opposite directions and terminating at the sides of the frame between pairs of vertically disposed stops 6 upon the frame. The ends of the short arms 4^b may be flattened or bent back upon themselves as shown for strengthening purposes. By the described formation the beater wires constitute bell-crank levers with the pin 5 at the angle, the longer arms pre-

senting the dasher portions proper 4^a. In operation the shorter arms 4^b, by their alternate contact with their respective upper and lower stops 6, during the reciprocation 55 of the bar 3, translate such reciprocatory movement into an oscillatory movement for the dasher portions proper. The distance between the upper and lower stops 6 permits a limited vertical movement of the beaters 60 with the bar, and such vertical movement with the oscillatory movement mentioned results in each dasher portion proper having an approximate elliptical oscillatory movement in a vertical plane.

The reciprocation of the bar 3 and consequent operation of the dashers is secured by means of a camplate 7 pivotally mounted upon the frame 2 and formed to present a series of exterior cam faces 8 in the path of movement of which a pin 9 carried by the upper end of the bar projects, each cam face graduating tangentially outward from the camplate proper to straight edge portion 8^a at an angle thereto which provides an abrupt 75 drop back to the camplate. Rotation of the camplate by a handle 9^a causes the graduated faces through pin 9 to move the bar upwardly and the straight edge portions 8^a permit it to drop, thus reciprocating the bar. 80

To avoid reliance upon gravity only for the downward movement of the bar I preferably provide a second pin 10 on the bar near its lower end and position the camplate between the pins, the cam faces being arranged in staggered relation so that immediately subsequent to the arrival at and passing of the straight edge 8^a of a cam surface beyond one pin during movement of the bar in one direction the graduated portion of an 85 opposite cam face engages the other pin and forces the bar in the opposite direction.

As shown I prefer to make the cam mechanism in plate form and by bending over the edges of the plate presenting the cam faces to form antifriction treads 11 preferably curved in cross section, which, with the pins 9 and 10 carrying antifriction rollers 12, means a much more satisfactory operation of the reciprocating bar and 95 through it the dashers.

It is also preferable that the straight edge

portions 8^a of the cams should be slightly inclined out of radial line or tangentially with relation to the camplate proper to establish obtuse angles therewith and so ease the drop of the reciprocating bar.

From the foregoing it will be noted that by use of the simple camplate mechanism reciprocating the bar in conjunction with the short bell-crank arm of the dasher wires 10 and the stops with which they contact, an approximate elliptical oscillatory movement in a vertical plane is imparted to the lower ends or dasher portions proper of the beaters and that the operating mechanism as a whole 15 is devoid of parts such as gears and pinions which are subject to much wear in the necessarily speedy operation of beaters of this character.

To simplify and cheapen construction the 20 frame 2 is, as shown, formed from a single length of wire, of a material and gauge to be easily manipulated and yet provide the requisite rigidity, first bent centrally of its length to form the handle portion 2^a of oval form, then to provide parallel spaced vertical side portions 2^b, upon which the operating mechanism is carried, and each side portion is then bent obliquely outward to a point, sufficiently beyond the dashers where it is 25 turned gradually to a right angled horizontal base section 2^c extending toward the opposite side to be again bent so as to extend obliquely upward and be connected as at 2^d to the opposite side portion at its point of divergence from the vertical.

It will be apparent that by such simple divergence of the lower portions of the frame wire and bending them to present the horizontal base sections 2^c the beater is provided with a base by which it can of itself stand upright.

To provide a substantial pivotal and steadyng mounting for the camplate 7 the side portions of the frame are bowed out 45 at 13 and have mounted thereon a bearing plate 14, secured in place by lugs 15 formed on the plate and bent to clasp such side portions, the bearing plate having a central opening to accommodate a retaining pin 16 and the edge of such opening being flanged 50 outwardly to form a pivotal boss 17 upon which a similar pivotal boss 18, formed by flanging the edge of a central opening in the camplate, rotatably fits, the camplate being held in place by the head 19 of the retaining pin.

Plate 14 provides the guides for the reciprocating bar 3, which is of flat strip form with its ends bent back upon itself at 60 3^a to lend rigidity thereto and strengthen it at the points at which the pins 9 and 10 are mounted, the plate presenting lugs 20, bent to loosely overlap the bar, and a flange 21, with a vertical slot 22 to snugly accommo-

date it, the slot being open to facilitate 65 assembly.

The side portions 2^b of the frame are joined and braced by a brace plate 23 located above and adjacent the point of their divergence from the vertical, such brace plate 70 spanning the space between the frame portions and having its side margins flanged to flank the sides, the lower portions 23^a of the flanges being bent around the frame portions to fasten the brace thereto, while the 75 upper portions 23^b present vertical slots 24 through which the short arms 4^b of the dashers protrude, the ends of the slots constituting the stops 6 to be engaged by such arms as before mentioned. The bottom 80 margin 23^c of the plate 23 is bent horizontally and formed with slots 23^d to receive and assist in maintaining in the required relative position the oscillating dasher arms, the slots being open at one end to facilitate 85 the entry of the beater arms during assembly, and the plate being also recessed at 23^e to accommodate the adjacent end of pin 5 carried by the reciprocating bar 3.

What I claim is as follows:

1. In a beater, a dasher having an approximate elliptical oscillatory movement in a vertical plane with means including a cam and a vertically reciprocating bar for causing such movement, the said bar having the 95 dasher pivotally mounted near its lower end and having its upper end immediately adjacent and in antifriction contact with the actuating surface of the cam.

2. In a beater, a dasher having an approximate elliptical oscillatory movement in a vertical plane with means including a cam, a vertically reciprocating bar having the dasher pivotally mounted near its lower end and having its upper end immediately adjacent and in antifriction contact with the actuating surface of the cam, and fixed stops, 105 with which a part of the dasher makes contact to swing the dasher, to produce said movement of the latter.

3. In a beater, a frame, a dasher of bell-crank form with a long arm presenting a dasher portion proper, a pair of stops on the frame with which a shorter arm of the dasher contacts, a bar pivotally carrying the 115 dasher and a cam for reciprocating the bar and causing the shorter arm to engage the stops in order to oscillate the dasher portion proper in an approximate elliptical oscillatory path in a vertical plane.

4. In a beater, a frame, a bar slidably mounted upon the frame, stops upon the frame, a dasher pivoted upon the bar and having one end extending to a position intermediate the stops, and a cam for reciprocating the bar and with it the dasher to cause the extended end of the latter to engage said stops in order to oscillate the

opposite end of the dasher in an approximate elliptical path in a vertical plane.

5. In a beater, a frame, a bar slidably mounted upon the frame, a pair of stops spaced longitudinally of the frame at each side thereof, a pair of dashers of bell-crank form pivoted to the bar and each having an arm positioned intermediate each pair of stops, and a cam for reciprocating the bar and with it the dashers to cause the positioned arms to engage said stops.

6. In a beater, a frame, a bar slidably mounted upon the frame, a pin carried by the bar near one end, a cam rotatably mounted upon the frame to engage said pin and reciprocate the bar, a dasher of bell-crank form pivoted upon the bar and reciprocated therewith, one arm of the dasher being formed as a dasher portion proper and extending downward and its other arm extended transversely of the frame, and stops spaced longitudinally of the frame above and below the transversely extended arm to be engaged thereby during its reciprocation in order to impart an oscillatory movement to the dasher portion proper.

7. In a beater, a frame, a bar slidably mounted upon the frame, a pin carried by the bar near one end, a camplate rotatably mounted upon the frame and presenting a plurality of cam faces to engage said pin and reciprocate the bar, a dasher of bell-crank form pivoted upon the bar and reciprocated therewith, one arm of the dasher being formed as a dasher portion proper and extending downward from the bar and its other arm extended transversely therefrom, stops spaced longitudinally of the frame above and below the transversely extended arm to be engaged thereby during its reciprocation in order to swing the dasher portion proper.

8. In a beater, a frame, a bar slidably mounted upon the frame, a pair of rollers carried by the bar and spaced longitudinally thereof, a camplate presenting a series of cam faces and rotatably mounted upon the frame in such a position between the rollers that such cam faces will successively engage said rollers and reciprocate the bar, a dasher of bell-crank form pivoted upon the bar and reciprocated therewith, one arm of the dasher being formed as a dasher portion proper and extending downward from the bar and its other arm extended transversely therefrom, stops spaced longitudinally of the frame above and below the transversely extended arm to be engaged thereby during its reciprocation in order to swing the dasher portion proper.

9. In a beater, a frame, a bar slidably mounted upon the frame, a pair of rollers carried by the bar and spaced longitudinally thereof, a camplate presenting a series of

cam faces therearound, in staggered relative relation, and rotatably mounted upon the frame in such a position between the rollers that such cam faces will successively engage said rollers and reciprocate the bar, the cam faces graduating outward tangentially from the camplate proper and terminating in a straight edge abruptly leading to the camplate proper and forming an obtuse angle therewith, a dasher of bell-crank form pivoted upon the bar and reciprocated therewith, one arm of the dasher being formed as a dasher portion proper and extending downwardly from the bar and its other arm extended transversely therefrom, stops spaced longitudinally of the frame above and below the transversely extended arm to be engaged thereby during its reciprocation in order to swing the dasher portion proper.

10. In a beater, a frame, a bar slidably mounted upon the frame, a pin carried by the bar near one end, a pair of wire dashers of bell-crank form pivoted upon the bar and each having one arm extended downwardly and bent to present a dasher portion proper of substantially flattened volutoid form, the convolutions of one dasher portion being of different measurement to the corresponding convolutions of the other to allow such portions to pass each other, and its other arm extended transversely outward across the frame, a pair of stops upon each side of the frame, one stop above and the other below said transversely extended arm, and a camplate rotatably mounted upon the frame and presenting a series of cam faces to engage the pin on the bar, reciprocate the latter and carry the transversely extended arms into engagement with the stops and so swing the dasher portions proper.

11. In a beater as claimed in claim 7, a bearing plate carried by the frame and having a retaining pin passing therethrough, the plate being formed with a boss encircling the pin and the camplate being centrally perforated and also formed with a boss encircling the perforation and adapted to be rotatably mounted on the boss of the bearing plate.

12. In a beater as claimed in claim 10, a brace plate carried by the frame and having a horizontal flange-portion presenting slots open at one end to receive and assist in maintaining in the required relative position the downwardly extended dasher arms.

13. In a beater of the character described, having a dasher, operating mechanism and a supporting frame for carrying the beater operating mechanism, such frame being formed from a single length of wire which is first bent centrally of its length to form at the upper end of the frame a handle

portion, further bent to provide parallel spaced straight vertical side portions upon which the operating mechanism of the beater is carried, and then each side portion 5 bent obliquely outward to a point, sufficiently beyond the dashers of the beater, where it is turned to form a right angled horizontal base section, extending toward the opposite side, to be again bent so as to ex-

tend obliquely upward and be connected to 10 the opposite side portion.

14. In a beater as claimed in claim 7, the edges of the cam faces being formed to provide anti-friction tread surfaces.

In testimony whereof, I have signed my name to this specification.

EDWARD M. MORGAN.
